WHEEL

Frederick W. Burger, Niles, Mich., assignor to
 Clark Equipment Company, Buchanan, Mich.,
 a corporation of Michigan

Application October 31, 1936, Serial No. 108,585

1 Claim. (Cl. 301—63)

This invention relates to wheels and more particularly is directed to disc wheel structures in which the rim is demountably secured to the disc.

In previous disc wheel constructions with which I am familiar, the rim has customarily been permanently secured to an outer flange on the disc, and the disc has been detachably secured by means of mounting studs to the hub of the wheel. Such constructions are objectionable for several reasons, such as the necessity for carrying an extra disc and wheel for use in case of blowouts or the like, the necessity for providing adequate mounting means at the hub portion of the disc to prevent loosening of the disc on the hub, and chucking of the discs when a dual wheel construction is employed.

My present invention contemplates broadly the provision of a disc construction so formed that the disc may be more or less permanently secured to the hub of the wheel, and a demountable rim can be mounted on the peripheral portion of the disc, thereby eliminating the necessity for carrying an extra disc and rim.

One of the main advantages secured by the present invention is the ability to provide a solid support for the disc at the hub of the wheel, and also to provide a construction which can be alternatively employed for either single or dual wheel assemblies. In connection with this feature, I preferably provide, in a dual wheel assembly, for a press-fit of the inner disc on the hub, thereby rigidly and more or less permanently attaching the disc to the hub so that no possibility of loosening of the clamping nuts or relative radial displacement of the disc with respect to the center of the hub can be effected. Thus, in my dual wheel construction the in-board disc is pressed onto a suitable shoulder on the hub, and the outer disc is more or less rigidly attached to the hub by means of clamping studs and bolts. Since, in case of punctures or blowouts, the tire rim can be detached from the disc without the necessity of removing the disc from the hub, this affords the advantage of allowing a more permanent type of mounting of the disc at the hub.

Another important advantage secured by the present invention is the provision of a disc which may be formed in the standard manner, and which need be subjected only to a relatively economic stamping operation in order to form it into a disc capable of carrying a demountable rim. This eliminates the necessity of the rivet connection between the rim and disc as in present disc wheel constructions, and insures

economic replacement of either the disc or rim in case of failure of one of these members. It is also within the purview of the present invention to form the disc as a casting, if so desired.

By reason of the semi-permanent fastening on the hub and the easy accessibility of the rim-supporting means at the periphery of the disc, the mounting and demounting of the rims independently of the discs is facilitated, and the operator is not required to shift as much weight in changing of a tire as required when both the rim and disc had to be removed from the hub and a new rim and disc secured thereto.

The present invention thus accomplishes important advantages in disc type mounting of wheels, while yet retaining a simple construction that is substantially as economical as previous disc constructions and is more efficient in the operation of changing tires or assembling and disassembling the construction.

Other objects and advantages of the present invention will appear more fully from the following detailed description which, taken in conjunction with the accompanying drawings, will disclose to those skilled in the art the particular construction and operation of preferred embodiments of my invention.

In the drawings:

Figure 1 is a front elevational view of a portion of a single wheel assembly embodying the present invention;

Figure 2 is a sectional view taken substantially on line 2—2 of Figure 1;

Figure 3 is a plan view laid out as a development of a portion of the periphery of the disc;

Figure 4 is a lateral sectional view through a dual wheel assembly embodying the principles of the present invention;

Figure 5 is a sectional view taken substantially on line 5—5 of Figure 3;

Figure 6 is a sectional view taken substantially on line 6—6 of Figure 3;

Figure 7 is a sectional view taken substantially on line 7—7 of Figure 3;

Figure 8 is a sectional view taken substantially on line 8—8 of Figure 3; and

Figure 9 is a sectional view taken substantially on line 9—9 of Figure 3.

Referring now in detail to the disclosure of Figures 1 and 2, the disc is indicated generally at 5 and is formed in any usual manner, preferably being provided with the cut-out portions 6 which serve to simulate a spoke construction and provide, in a dual wheel assembly, openings 55

through which the inner valve stem may be reached.

The disc of Figure 1 in section is shown substantially as indicated in Figure 2, having the 5 reentrant portion 7 which terminates in the radially inwardly extending flange 8 which is secured to the hub of a wheel, preferably by a press-fit, over laterally projecting clamping studs (not shown), and which is held against lateral displacement by means of clamping nuts engaging the lateral surface of the disc. This provides for centering the disc accurately with respect to the hub, and insures that the disc will have no radial movement with respect to the hub, which 10 is distinctly advantageous when considered in connection with previous constructions in which the inner peripheral edge of the disc was loosely slipped over the hub and held in position only by the clamping studs, which had to take all 15 of the load as well as the torque.

The outer peripheral edge of the disc is provided with a tapered substantially conical peripheral surface indicated at 9 which, at circumferentially spaced portions, is provided with recesses 10 formed by a stamping operation which presses the wall 12 of the disc into radial position to form an axially outwardly opening socket adapted to have the clamping bolt 13 extending therethrough for receiving the clamping lug 14 20 which is provided with a heel portion 15 engaging the lower portion of the wall 12 and with a lip portion 16 engaging the lateral edge of the beveled portion 17 of the rim 18. Upon tightening of the nut 19 on the bolt 13, the lug 14 is heeled about the point 15 to wedge the rim 18 laterally inwardly on the tapered surface 9 to fix the rim laterally and radially in position on the disc.

Considering now in detail the dual wheel assembly shown in Figure 4, the hub for the wheel is indicated generally at 20 and is adapted to have bearing seating portions 22 for receiving the bearings, rotatably mounting the hub on the end of the axle housing. The axle is indicated at 23 and has the outer flanged portion 24 which is secured to the outer radial face of the hub 20 by means of the bolts 25, thereby securing the hub to the spindle 23 for driving engagement.

The hub is provided with a radially extending 50 flange portion 26 having spaced rearwardly extending bosses 27 terminating at their radial inner portions in annular seats 28 receiving the head flange 29 of a brake drum 30. The drum 30 is secured to the hub by means of the bolts 32 which extend through the flange 26 and the bosses 27, and are threaded to receive the nuts 33 for clamping the drum rigidly to the flange. A brake closure plate 34 is preferably clamped 55 between the bolts 33 and the flange 29 of the drum, and encloses the inner end of the hub 20.

On the outer face of the flange 26, an annular seat 35 is provided which is adapted to be engaged by the inner defining edge of the inwardly extending portion 36 of an inboard disc 37. The disc is adapted to have a press-fit over the shoulder 35 and is moved into abutting engagement with the outer radial face of the flange 26, whereby it is fixed in position on the hub 20 independently of the clamping means. However, the bolt 60 32 extends through the disc 37 and is provided with a collar portion 38 serving to hold the disc against outer lateral displacement, the disc having the portion adjacent the collar peened over the outer face thereof.

The disc 37 corresponds somewhat to the disc

5 previously described, except that the peripheral conical flange portion 40 is offset laterally inwardly with respect to the lateral inwardly extending portion 36. Adjacent the outer periphery of the disc 37, a plurality of outwardly opening sockets 42 are provided corresponding to the sockets 10, terminating in radially extending transverse walls 43 and receiving clamping bolts 44 which extend therethrough and which carry the clamping lugs 45 having the heel portions 10 46 bearing against the radial inner ends of the walls 43, and having the outer lip portions 47 bearing against the outer marginal edge of the rim 48. Suitable nuts 49 serve to move the lugs 45 inwardly on the bolts 44 to wedge the rim 48 15 into fixed seating engagement on the flange 40 of the disc.

The outboard disc 50 is similar to the inboard disc but is provided with the tapered socket portions 52 adjacent the inner periphery thereof, 20 which receive the projecting ends of the bolts 32 and which are engaged by the wedge portions 53 of the locking nuts 54. This provides for moving the disc 50 into lateral abutting engagement with the outer radial face of the portion 36 of 25 the disc 37, and also centers the disc with respect to the hub 20. The nuts 54 lock the disc in fixed position on the studs 32 and may be of such size as to form a more or less positive and rigid support for the outboard disc.

The nuts 54 also serve to clamp the annular ring member 55 in position against the outer face of the disc 50, this ring member being provided with an annular outwardly facing groove 56 adapted to receive the beaded edge 57 of a hub cap 58 which encloses the clamping studs and the outer end of the hub 20 and spindle 23. The disc 50 is adapted to receive a rim 60 corresponding to the rims 18 and 48, each of these rims being provided with the driving plates or driving 40 lugs 62 secured to the inner web surface thereof and also being provided with apertures 63 which receive the inwardly extending valve stem members 64 connected to the inner tubes carried by the tires supported on the rims. The rims are of 45 more or less conventional design of the type used on cast metal wheels.

The discs 37 and 50 are formed at their outer periphery substantially in the same manner as the disc 1, but have the radial inner clamping 50 portions which engage the hub disposed in laterally offset position with respect to the peripheral rim portions in order that the proper spacing between the rims 48 and 60 may be obtained.

In Figure 3 there is disclosed a development of 55 a portion of the periphery of the disc, this being typical of any one of the discs 1, 37, or 50. For purposes of description, the disc 37 will be considered as the disc shown in Figures 3, and 5 to 9, inclusive. It will be noted from Figure 3 that the socket portion 42 is provided with defining wall portions 70 which are shown more in detail in Figure 9, the walls 70 terminating at their upper ends in the laterally projecting spaced seating portions 72 which initially center the 65 rim on the disc, these seating portions merging into a continuation of the tapered surface 40 of the periphery of the disc. The transverse wall 43, which has the aperture 73 for receiving the clamping bolt 44, extends substantially radially of the disc and terminates the axial inner end of the socket portion 42. The normal extent of the tapered portion 40 of the disc is indicated by the dotted line 74 which indicates that the seating portions 72 are formed only adjacent the socket 75

portion 42 about the periphery of the disc. Thus, as shown in Figure 7, the seating portions 72 extend laterally and circumferentially on opposite sides of the socket 42, and provide initial 5 rim-centering surfaces which will center the rim prior to its being wedged upwardly on the beveled portion of the periphery of the disc.

In order to accommodate the valve stem carried by the inner tube supported on the rim, the 10 rim is suitably stamped, as indicated at 75, to provide a relatively deep radial recess for receiving the valve stem member. This recess is flanked on opposite sides by circumferentially spaced radially extending shoulders which are 15 indicated in Figures 5 and 6 by the reference numeral 76. Intermediate the shoulders 76 and on opposite sides of the recess 75, there is a recessed portion provided by the walls 77 which allows the driving lugs 62 of the rim to be seated 20 thereon, and to engage against the oppositely facing shoulders 76 for preventing rotation of the rim with respect to the disc. The driving lugs are located on opposite sides of the valve stem opening for the rim and, consequently, center the 25 valve stem in the recess 75 when engaged with the shoulders 76. As shown in Figure 8, the normal peripheral extent of the disc intermediate sockets 42 provides the tapered surface 40 which forms the seating surface for the beveled marginal edge of the rim, and is provided at points 30 corresponding to the spacing of spokes about the disc 37 with laterally projecting rim-centering portions 72 struck outwardly of the peripheral margin of the disc on opposite sides of the lug-receiving sockets 42.

The disc may be formed into the shape disclosed in Figure 3 by any desired stamping operation, preferably when the disc is initially formed, which produces the lug-receiving sockets, the 40 driving shoulders and the valve stem recess, in addition to the shoulders 72, forming initial rim-centering means. This provides a very economical construction, which includes the advantageous feature of allowing for detachable mounting of the rim on the periphery of the disc whereby the disc may be more or less permanently secured to the hub and need not be displaced in order to remove the rim.

In the assembly shown in Figure 2, the disc 7 45 is permanently secured to the hub of the wheel and, in case of deflation of the tire carried by the

rim 18, the rim can be readily demounted by removing the clamping lugs 14 and allowing the rim to be withdrawn laterally from the disc.

It is sometimes desirable to mount a second tire on the front wheel, as in the case of Army 5 trucks traversing broken ground. This may be accomplished in the present invention by clamping a second disc to the studs over which the disc 7 is pressed, much in the same manner that the disc 50 is mounted with respect to the 10 disc 37. While this does not provide any appreciable tire spacing due to the shape of disc 7, the construction is extremely advantageous in increasing the contact area supporting the weight 15 of the vehicle, and prevents the wheels from sinking down in soft ground.

It is therefore apparent that I have provided a novel type of demountable disc wheel construction which embodies features of utility not heretofore possible in structures with which we have 20 been familiar. The cost of the present construction is not appreciably greater than the cost of an ordinary type of disc wheel assembly in which the rim and disc are permanently secured together, and due to the fact that the necessity of 25 carrying an extra disc is eliminated, an economical construction is provided. Further, the present construction eliminates the problem of securing the disc to the hub, since the disc can be more or less permanently secured to the hub 30 and thus avoids a number of objectionable features of previous constructions.

I do not intend to limit this invention to the exact type of disc construction herein shown and 35 described, but only insofar as defined by the scope and spirit of the appended claim.

I claim:

A wheel disc adapted to be secured to a hub and comprising a frusto-conical body portion terminating in a circumferentially continuous 40 beveled flange, and a series of circumferentially spaced recesses in said body portion at the radial inner end of said flange, each of said recesses comprising a radially outwardly opening U-shaped socket extending axially and having the 45 radial outward ends of its sides defining walls merging circumferentially with flanges projecting axially outwardly from the surface of said flange to form circumferentially spaced abutments thereon.

FREDERICK W. BURGER.
